UNITED STATES PATENT OFFICE

139,341

DESIGN FOR A HYDRAULIC JACK

Herbert E. Page, Alhambra, Calif.

Application August 15, 1944, Serial No. 114,887

Term of patent 14 years

(Cl. D41—1)

To all whom it may concern:

Be it known that I, Herbert E. Page, a citizen of the United States and resident of the city of Alhambra, county of Los Angeles, State of California, have invented a new, original, and ornamental Design for Hydraulic Jack, of which the following is a specification, reference being had to the accompanying drawings forming a part thereof, in which:

Fig. 1 is a top plan view of a hydraulic jack, showing my new design;

Fig. 2 is a front end view;
Fig. 3 is a bottom plan view;
Fig. 4 is a side elevational view;
Fig. 5 is a perspective view; and
Fig. 6 is a rear end view thereof.

I claim:

The ornamental design for a hydraulic jack, substantially as shown.

HERBERT E. PAGE.
